W. W. BLAKELY

GARAGE DOOR HOLDER

Filed Oct. 15, 1923

By Whitemore, Hubert, Whitemore, and Belknap
Attorneys

Inventor
William W. Blakely

UNITED STATES PATENT OFFICE.

WILLIAM W. BLAKELY, OF DETROIT, MICHIGAN.

GARAGE-DOOR HOLDER.

Application filed October 15, 1923. Serial No. 668,751.

This invention relates to holders for retaining garage doors or other hinged closures in open or partially open position.

The invention consists in employing a bracket or the like to pivotally connect a brace member to a swinging closure, said bracket having a pocket or the like into which the pivotal end portion of a brace member is adjustable to retain said member in a stored position upon the closure.

In the drawings:—

Figure 1 is an edge view of a door equipped with the improved holder disclosing the latter in its position of use;

15 Figure 2 is a similar view but showing to an enlarged scale the means connecting the bracing member to the door and indicating in dash lines the stored position of the brace member;

20 Figure 3 is an interior view of the portion of the door to which the invention is attached;

Figure 4 is a cross section on line 4—4 of Figure 3 but disclosing the brace member in stored position;

25 Figure 5 is a view of the sheet metal blank from which is fashioned the bracket attaching applicant's bracing member to the closure.

30 In these views the reference character A designates a swinging garage door or other closure and B is a metal rod forming a brace, which in use assumes an inclination to the door, as best seen in Figure 1, said rod being pivoted to the door at one end and engageable at its other extremity with the surface above which the door swings. For connecting said rod to the door there is preferably employed a bracket C formed from a

35 sheet metal stamping. The upper and the lower end portions C' of said bracket lie against the interior face of the door and are engaged by screws D securing the bracket in place. The stamping from which the bracket is formed has opposed openings E just below its upper portion C', said openings being of an L-shape with downward extensions E' between which a neck portion F is formed. Just above the lower end portion

40 C' the bracket has opposed notches G in its vertical margins. The neck portion F of the bracket and the portion intermediate the notches G are bent to locate the central portion of the bracket in a plane spaced from that of the end portions C' and the margins

45 G' of said central portion are bent toward

the plane of the ends C'. Thus, when the bracket is secured to a closure as A, a vertically elongated pocket H is formed by the central portion of said bracket. For pivotally engaging the brace rod B with said bracket an end portion of the rod is bent to the form of an elongated loop I, which loop embraces the neck F of the bracket. When the device is not in use the rod B is swung to 60 the vertical position indicated in dash lines in Figure 2 and is then lowered to engage its pivotal end portion in the pocket H to maintain the rod in inverted position against the door A. The elongation of the loop I 65 permits such vertical movement of the rod B as is necessary to engage the looped end within said pocket or to withdraw said end therefrom. When in engagement with the pocket H, the brace member is so confined 70 as to securely hold it in vertical inverted position. It will be noted from Figure 2 that the neck F is of a gooseneck form, being deflected outwardly somewhat beyond the central portion of the bracket to produce an ample space between said neck and the closure A to permit a free pivotal movement of the rod B. Moreover the upper wall F' of the neck projects outwardly at substantially right angles to the closure A, hence serves 75 as a shelf on which the converging portions B' of the rod may rest when in upright position in the pocket H. By forming the opposed openings E of the bracket with downward extensions E', the neck F is elongated 80 to permit fashioning thereof to the desired gooseneck form and the margins of the center portion, which form the sides of the bracket, are extended upwardly somewhat 85 beyond the center portion of the bracket so as to add somewhat to the length of the pocket H.

90 The described door holder is adapted for inexpensive manufacture and is quickly adjustable from its position of use to a stored position, in which it is entirely out of the way.

95 What I claim as my invention is:—

1. In a device of the character described, the combination with a hinged closure, of a 105 brace member for holding said closure in an open position, and a bracket on said closure extending through said brace member and having an elongated pocket for receiving an end portion of the brace member to maintain a stored position thereof.

110 2. In a device of the character described,

the combination with a closure, of a brace member pivotally connected thereto for holding the closure in an open position, and a bracket on said closure extending through 5 said brace member, said bracket having a pocket engageable by an end portion of the brace member to maintain a stored position of the latter.

3. In a device of the character described, 10 the combination with a closure, and a brace member for retaining said closure in an open position, of a bracket on said closure extending through said brace member and pivotally engaged by said brace member, 15 said bracket forming a pocket elongated in parallelism to the surface of the closure to which the bracket is secured, the lower end of the pocket being closed for supporting the pivotal end of the brace member the 20 brace member having both a pivotal and a sliding movement relative to said bracket, the latter movement providing for entering the pivotal end of the brace member in said pocket following an upward pivotal movement of the brace member into parallelism with said closure.

4. In a device of the character described, the combination with a closure, of a brace member having a loop portion, and a bracket 30 attaching said brace member to the closure having a neck engaged by said loop, and a pocket adjacent said neck into which the looped portion of the brace member is slideable when said member is pivotally shifted 35 into substantial parallelism with the closure.

5. In a device of the character described, the combination of a brace member therefor, and a bracket member extending through the 40 brace member and pivotally mounting said brace member upon the closure, said bracket member having a longitudinally extending pocket providing for a downward movement of the brace member in an inverted position of proximity to said door, the lower end 45 of the pocket being engageable by the brace member upon such downward movement thereof to maintain said inverted position.

6. In a device of the character described, the combination with a closure, of a brace 50 member therefor, having a looped pivotal end, a sheet metal stamping secured to said closure and fashioned to form a neck pivotally engaged by the looped end of the

brace member, said loop being elongated to provide for a movement of the brace member 55 in substantial parallelism with said door, and means upon said bracket adjacent said neck engageable with the looped portion of the brace member upon such parallel movement to maintain the parallel relation of the 60 brace member to the door.

7. In a device of the character described, the combination with a closure, of a brace member therefor having a looped pivotal end portion and a sheet metal stamping secured to said closure and fashioned to form a neck engaging in the loop of the brace member to pivot the latter and further fashioned to engage said looped end to hold the brace member in substantial parallelism 70 with the closure upon a predetermined movement of the brace member parallel to the closure.

8. The combination with a closure, of a brace therefor including a rod having a loop portion, and anchorage means for the brace including a bracket on the closure having an open return-bent portion extending upwardly through the loop. 75

9. The combination with a closure, of a 80 bracket secured to said closure having a portion spaced from the closure and a return bent portion projecting outwardly from the closure above the portion aforesaid, and a brace having an elongated loop at one end 85 pivotally mounted in said return-bent portion and movable longitudinally thereof into the space between said closure and the first mentioned portion of said bracket.

10. The combination with a closure, of a 90 brace rod therefor having an elongated loop at one end, and means on the closure for supporting the brace including a bracket having an open return-bent portion projecting outwardly from the closure and extending through the loop portion, the lower 95 wall of the return-bent portion constituting a pivot bearing for one end of the loop portion, and the upper wall of said return-bent portion constituting a seat for the opposite end of the loop when the rod is in an 100 upright position.

In testimony whereof I affix my signature.

WILLIAM W. BLAKELY.
